UNITED STATES PATENT OFFICE.

NEIL PATTERSON, OF WEST LINE, PENNSYLVANIA.

HEAD FOR ACID-CONTAINING RETORTS.

SPECIFICATION forming part of Letters Patent No. 664,891, dated January 1, 1901.

Application filed May 29, 1900. Serial No. 18,443. (No model.)

To all whom it may concern:

Be it known that I, NEIL PATTERSON, a citizen of the United States, residing at West Line, in the county of McKean and State of Pennsylvania, have invented a new and useful Head for Acid - Containing Retorts, of which the following is a specification.

This invention relates to acid-containing retorts—for instance, such as are used in the manufacture of wood-alcohol. In such retorts the acid is very strong and soon destroys the heads of the bolts in the heads of the retorts and also destroys the joints between the head and the door therein, thereby resulting in a leakage of the contents of the retort. In view of this difficulty the present invention has been designed to obviate the leakage of the joints and to protect the bolts and also to provide an improved form of removable packing for the joints, so that they may be conveniently replaced when affected by the acid.

With these and other objects in view the present invention consists in the combination and arrangement of parts, as will be herein-after more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the drawings, Figure 1 is an elevation of the inner side of the head of a retort constructed in accordance with the present invention. Fig. 2 is a transverse sectional view thereof.

Corresponding parts are designated by like characters of reference in both figures of the drawings.

Referring to the drawings, 1 designates a plate forming a head of circular or other shape, which is provided with a marginal series of perforations 2 for the reception of fastenings, whereby the head may be secured to the shell of an acid-containing retort of any character whatsoever. Provided centrally of the head is an opening 3 of any preferred shape, whereby access may be had to the interior of the retort. This opening is normally closed by means of a door 4, which is hinged to the outer side of the head by means of any character

of hinge 5, as shown in Fig. 2 of the drawings, and adapted to fold into the opening, so as to be flush with the inner side of the head. At 55 the inner side of the opening in the head is an inwardly-directed flange 6, which is formed by means of a ring, removably secured to the inner side of the head by means of suitable fastenings, such as bolts 7, which have the 60 nuts 8 thereof located upon the outer side of the head. Held between the ring and the adjacent face of the head is a packing-ring 9 of asbestos or other suitable material, so as to form a tight joint between the ring and the 65 head.

The door is designed to close against the marginal flange as a stop to limit the inward movement thereof and is provided with a packing-ring 10 to fit against the flange 6, and 70 thus form a tight joint between the door and the flange. To hold the packing against the inner face of the door, there is provided a clamping metal ring 11, which bears against the packing and is held in place by means of 75 bolts 12, which pass through the ring and the door and have their nuts located upon the outer sides thereof. All of the bolts have their heads protected by means of caps or enlargements 13, cast upon the same, so as to 80 provide abnormally large heads, which are not so soon eaten away by the acid.

From the foregoing description it will be seen that the present invention provides an exceedingly simple and effective head for 85 acid-containing retorts, in which the joints thereof are made acid-tight, and the packing and retaining rings may be fitted in place through the opening in the head without removing the latter or the door; also, the bolts 90 are provided with protective caps or heads to prevent the former from being destroyed by the acid, and some of the bolts which secure the metal rings in place may also be employed to connect the hinges to the head and to the 95 door.

In practice I prefer to place the bolts with-in the molds that form the respective rings 6 and 11, so that the bolts may be cast there-to, the enlarged heads or protective caps 13 100 being cast at the same time.

What is claimed is—

1. A head for acid-containing retorts, having an opening therein, an inwardly-projecting

marginal flange at the inner side of the opening, an outer door hinged to the head and closing into the opening and against the flange, one or more packing-rings, and removable bolt-fastenings therefor, said bolts having acid-protected heads located upon the inner side of the retort, and nuts upon the outer side of the retort.

2. In an acid-containing retort, a head-plate having an opening therein, a removable flange secured to the inner side of the head-plate and overlapping the edge of the opening, a packing removably held between the flange and the head-plate, and also terminating at the edge of the opening, a door hinged at one side of the opening and to the head-plate, and swinging into the opening and against the flange, a packing-ring applied to the inner

side of the door and extending to the outer marginal edge thereof and fitting against the exposed portion of the flange on the head, a removable metallic ring clamping the packing-ring between the door and said metallic ring, and bolt-fastenings, some of which connect the flange to the head-plate, and others connect the metallic ring to the door, all of the fastenings having abnormally-enlarged acid-protected heads upon the inner side of the retort, and nuts upon the outer side thereof.

In testimony that I claim the foregoing as my own I have hereto affixed my signature in the presence of two witnesses.

NEIL PATTERSON.
